(57) **CLAIM**

The ornamental design for a coin holding base for decorative articles, as shown and described.

DESCRIPTION

FIG. 1 is a front perspective view of a coin holding base for decorative articles showing our new design, shown in a used condition with a heart and stick shown in broken lines; FIG. 2 is a front elevation view thereof; FIG. 3 is a back elevation view thereof; FIG. 4 is a right side view thereof; FIG. 5 is a left side view thereof; FIG. 6 is a top view thereof; and, FIG. 7 is a bottom view thereof.

The broken lines of the heart shaped decorative article in FIG. 1, the “Las Vegas” script shown in FIGS. 1, 2, and 6 and the coin in FIG. 6 form no part of the claimed design.

1 Claim, 4 Drawing Sheets
